UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

SWIVELED CUTTER HOBBER.

Application filed December 11, 1926. Serial No. 154,054.

This invention is a further advance in my progressive development of balanced drive hobbers along the line initiated by my earlier Patent No. 1,472,767 and subsequently carried forward by my later Patent No. 1,603,258. In the earlier case, the balance was attained in what might be termed a single purpose machine embodying two index gears, and in the later instance it was attained in a machine of greater range in which the compound index gears embodied four distinct gears. In each case, the general organization illustrated a shiftable work-carrier.

The present advance aims to attain (through a condensed and simplified structure) the advantages of a balanced drive of adequate range yet containing but three index gears, as well as the advantages flowing from a work-carrier in the nature of an anvil as distinguished from a shiftable work-carriage. Each of these characteristics mutually cooperate towards reducing vibration or chatter, the bête noire of "production" machines; in the case of the balanced drive by avoiding preponderating sources of backlash between the serial elements of the tool-driving and the work-driving transmissions, respectively, and in the case of the anvil-like work-support by presenting the greatest practicable rigidity in opposition to the hammering impacts of the successively acting cutter blades.

By making a shiftable work-carrier sufficiently massive, its responsive vibrations may become unobjectionable, but an undue increase in the gross weight of the machine is thereby necessitated. But by making the work-carrier non-shiftable and in effect integral with the bed, the normal mass of the bed becomes available as an anvil (and other conveniences are had) and all without adding metal to the carriage.

In departing from convention, as aforesaid, this invention takes advantage of the fact that the stanchion is normally heavy and massive. It is now proposed to make it shiftable, (instead of the work-carrier) for

the dual purpose of obtaining adjustment needed and at the same time procuring the effect of a shiftable anvil. This, furthermore, is accomplished by a reorganization of the transmission system in such a manner that a condensed balanced drive is provided for propelling the spindles and for accommodating the body-shift of the stanchion.

To illustrate how the foregoing characteristics may be mechanically embodied in a coordinated mechanism, drawings are annexed and, in these, Fig. 1 is a side elevation of a hobbing-machine showing a fixed work spindle and a shiftable stanchion supporting a hob-carrying head slidable thereon; all in combination with a compatible simplified balanced drive comprising but three index gears. Fig. 2 is a skeleton of the balanced-drive transmission system for performing the various movements of the working and positioning elements of the machine. Figs. 3 and 4 are rear and front end-elevations, respectively, of the machine showing further details of the manner of combining the balanced drive with the major frame-elements of the machine.

The bed A, in this embodiment, is elongated and positioned horizontally and provides a forward working region in which the work spindle is directly journaled so as to occupy a fixed position, and the bed provides also a rear mechanism-supporting region on which the stanchion is slidably mounted. The work spindle W is shown journaled in fixed bearings A and it extends downwardly into the interior of the bed as indicated by W' and, at its lower end, carries a worm-wheel W² by which it is driven. The portion of the bed that houses the worm-wheel W² is appropriately enlarged to contain that wheel and, inasmuch as the wheel occupies a fixed position in space, the bed admits of being ribbed and reinforced closely to the wheel and thus made very rigid as will be understood without illustration. It is noteworthy that by thus giving the work spindle a fixed position at the forward end of the bed, it is at all times quickly

accessible to the user and it is not at one time further from the end of the bed than at another as often happens when the work spindle is shiftable in position. The mounting of the spindle is accomplished in a very solid manner with the object of realizing the effect of an anvil so that it virtually supports the work substantially as solidly as though it was clamped to the bed itself and, 10 in consequence, the tendency to vibrate and chatter is reduced to a minimum.

The stanchion S is in the nature of a heavy box-like casting which is provided with slideways S' and S^2 at right angles to 15 one another; the slideways S' resting on the slideways S^2 provided by the surface of the bed and arranged to permit the heavy stanchion to be slid towards and away from the axis of the work spindle for the purpose of 20 determining the diameter of the gear G to be cut by the machine. The purpose of the transverse slideways S^2 is to support and guide a head H which is thus shiftable in parallelism with the axis of the work-spindle so that the cutter or hob (which is carried by the head) may in the course of the 25 feeding movement cut the teeth of the gear G . It will be understood that this head H is suitably gibbed to the slideways S^2 and, 30 in order to counterbalance the weight of the head H , a counterweight H^4 may be arranged to rise and descend in an appropriate well provided by the stanchion S ; conventional ropes and pulleys H^2 and H^3 being provided as will be understood.

It is to be noted that the stanchion, being heavy and massive, is in effect a part of the solid bed itself because when clamped down to that bed, it becomes very solid therewith 40 owing to the action of the clamps augmented by the weight of the stanchion and by reason of the fact that the base of the stanchion S is very extensive so as to resist effectively such overturning forces as result from the 45 pressure of the hob against the work during the tooling operation. It will likewise be noted that, in cutting spur gears, the stanchion requires to be shifted only when a change is to be made in the diameter of 50 the spur gears being cut (which ordinarily would be quite infrequent) and it will also be noted that the shifting of the stanchion does not reduce the facility of access of the user to the work spindle and does not interfere 55 with obstructions when brought closer to that spindle. It will also be noted that the slideways S' at the base of the stanchion runs to a region substantially underlying the head H so that this construction avoids the 60 objectionable overhang which is necessitated whenever the work spindle is mounted on a carriage which slides on the bed.

The simplified transmission system for rotating both the work spindle and the hob, 65 and for progressively feeding the head H ,

and for shifting the position of the stanchion S , and for varying the rates of rotations and for shifting the parts quickly or slowly as the case may be, will now be described.

This transmission is in the nature of a balanced drive and comprehends an intermediate splined shaft X and two main transmission shafts Y and Z ; the hob-driving shaft Y being also splined. These two shafts are disposed at right angles and the 75 splined intermediate shaft is parallel with one of them; the latter being in this embodiment the non-splined shaft that communicates motion to the work spindle. The intermediate shaft receives the power in the first instance; this being accomplished by the power-line consisting of a pulley P or other prime-mover, the power shaft P' and appropriate gears such, for example, as the 80 two spur gears P^2 and P^3 and the two angle 85 gears P^4 and P^5 .

The hob-driving splined transmission shaft Y is journaled in the shiftable stanchion so as bodily to travel therewith in a direction parallel with the intermediate shaft and, at its lower end, it is provided with an angle gear y' which meshes with a shiftable angle gear x' which is splined to the intermediate shaft X . With respect to the hob-spindle, the head 3 has a suitable bracket 33 which journals the angle-gear x and causes it to slide on the shaft Y (to which it is splined) and be kept in true mesh with the angle gear y of the unit $y-e$ which is likewise journaled on the head 3 transversely to the shaft Y ; the axis of the unit $y-e$ being utilized as an off-set center of 90 swivel for the hob bearing 30 . A worm c' on the hob spindle meshes with the worm e . It may be noted here that, since that center of swivel is off-set, the hob may not be swiveled through such a wide range of angles as if the center of swivel had been coincided with the center of the hob and thus the range of the machine is to that extent restricted; but the advantage is that the construction is greatly simplified and requires precisely the two gears extra (one tooth contact) required to balance the drive 95 in combination with the same number of two extra pairs of intermeshing tooth contacts provided respectively by the index change gears x^2 , I and $I-e^2$ employed as extra change gears for materially extending the range of speeds of the work relative to 100 the cutter. In other words, the employment of the three change gears x^2 , I and e^2 (yielding two tooth contacts) is made possible without disturbing the balance of the drive of the spindles, by using also the two extra gears x and y , (yielding one tooth contact) and conversely and thus not only is the speed 105 range extended through the three change-gears but the hob may be disposed at various incidental angles within a considerable 110

115 range of speeds of the work relative to the cutter. In other words, the employment of the three change gears x^2 , I and e^2 (yielding two tooth contacts) is made possible without disturbing the balance of the drive of the spindles, by using also the two extra gears x and y , (yielding one tooth contact) and conversely and thus not only is the speed 120 range extended through the three change-gears but the hob may be disposed at various incidental angles within a considerable 125 range of speeds of the work relative to the cutter. In other words, the employment of the three change gears x^2 , I and e^2 (yielding two tooth contacts) is made possible without disturbing the balance of the drive of the spindles, by using also the two extra gears x and y , (yielding one tooth contact) and conversely and thus not only is the speed 130 range extended through the three change-gears but the hob may be disposed at various incidental angles within a considerable

range from the fixed or predetermined base-angle. These three gears provide two pairs of tooth contact, i. e., between gears x^2 and I, and between I and z^2 . This affords six pairs of tooth contacts; three being used to transmit the motion from the connection with the prime-mover to the hob-spindle, and likewise three to the work-spindle. The one set of three tooth contacts is provided by the gear pairs $x'y'$, xy and ee' . The other set of three tooth-contacts is provided by the gear pairs x^2I , Iz^2 and $z'W^2$.

The other non-splined transmission shaft Z is journaled in the bed of the machine and has a worm z' affixed thereto for driving the spindle W through the worm-wheel W^2 .

To start the machine, the power lever B is actuated. This shifts the collar 8 and slides a long key 9 (which is translatable counter-sunk in the shaft P') and this key actuates a suitable clutch (not shown) between the prime-mover P and the shaft P'. The transmission elements previously described are then maintained in motion by the power imparted to the intermediate shaft and the cutter and the work are both revolved at the relative rate determined by the three change gears z^2 , I and x^2 .

To manually shift the stanchion a hand-wheel V (provided with graduations or micrometer adjustments) is affixed to a shaft that carries an angle gear V' which meshes with an angle gear V ^{2} which is splined to the screw S ^{2} and enables it to be turned by hand. That screw is appropriately journaled and threaded, respectively, between a fixed part of the frame and a part shiftable with the stanchion. The above described manual means enables the user very readily to bring the stanchion to any desired position with respect to the work-spindle for cutting spur-gears.

To feed the cutter head, the parts will be in the positions and relations shown best by Fig. 2. The feeding motion is conveyed by a transmission consisting of an angle gear 1 mounted on the shaft Z and meshing with an angle gear 2 affixed to the shaft 3. A worm 4 on that shaft drives a worm-wheel 5 which turns the shaft 6 and, through appropriate change-gears designated generally by 7, the gears r^2 is driven and this gear is arranged to drive the shaft F ^{6} , as for example, by being affixed to a sleeve r which is loosely mounted on the shaft F ^{6} but adapted to be connected thereto by the clutch-teeth r' by bodily shifting the sleeve r. Angle gears F ^{5} and F ^{4} transmit the motion from the shaft F ^{6} to the shaft F ^{3} which is journaled in the stanchion and, at its upper end, has a gear F ^{2} which meshes with a gear F' which is a unit with a nut that turns about the non-rotatable feed-screw F. That feed-screw is affixed to the head H and is caused to move up or down, as the case may be, by the ro-

tating nut and, in this manner, the cutter journaled on the head H is caused to feed downwardly whenever the parts are connected up as described.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be comprehended within the meaning and range of equivalency of the following claims.

Having thus revealed this invention, I claim as new and desire to secure the following combinations and elements, or equivalents thereof, by Letters Patent of the United States:

1. A hobbing-machine combining a hob-supporting spindle; means for shifting said spindle laterally in either one of two transverse directions; a work-supporting spindle; a transmission connecting said spindles and consisting of but three shafts and gears providing six pairs of tooth-contacts; a prime-mover geared directly to one of the intermediate parts whereby the power for driving each of said spindles will be transmitted by but three tooth contacts, one of the gears used for propelling the laterally shiftable hob-supporting spindle having its axis extending in a direction transverse to the axis of said work-supporting spindle and being splined to the shaft on which it is mounted; and means for effecting a translation of said hob-supporting spindle in directions parallel with and transverse to the work-supporting spindle.

2. A balanced-drive hobbing-machine comprising a bed; a relatively heavy stanchion shiftably supported thereon; a work-supporting spindle non-shiftably journaled in said bed near one end thereof; a splined shaft and a parallel transmission shaft, each journaled on said bed transversely to said spindle; three serially arranged change gears connecting said two shafts; a splined transmission shaft journaled on said stanchion parallel with said spindle; a head slideable on said stanchion; a hob-supporting spindle swivelably mounted on said head; gears providing two pairs of tooth-contacts connecting said hob spindle with said splined transmission shaft, one of said gears being splined to said shaft; a pair of gears connecting said stanchion shaft to said first-mentioned splined shaft, one of said gears being splined thereto; and a pair of gears connecting said parallel transmission shaft with said non-shiftable work spindle.

3. A balanced-drive hobbing-machine com-

prising a bed; a relatively heavy stanchion shiftably supported thereon; a work-supporting spindle non-shiftably journaled in said bed near one end thereof; a splined 5 transmission shaft journaled on said stanchion parallel with said spindle; an intermediate splined shaft and a parallel transmission shaft, each journaled on said bed transversely to said spindle; change gears 10 providing two pairs of tooth contacts connecting said two shafts; a head slideable on said stanchion; a hob-supporting spindle mounted on said head; gears providing two pairs of tooth contacts connecting said hob 15 spindle with said splined transmission shaft, one of said gears being splined to said shaft; a pair of gears connecting said splined shaft to said intermediate splined shaft, one of said gears being splined to said intermediate 20 shaft; and a pair of gears connecting said parallel transmission shaft with said non-shiftable work spindle.

4. A balanced drive hobbing-machine combining a bed having a slideable stanchion; a 25 head slideable thereon; a hob supporting spindle swivelly mounted on said head; a carriage fixed on said bed; a work-supporting spindle on said carriage; a three-shaft transmission connecting said spindles, two 30 of said shafts being arranged parallel to each other and one of said parallel shafts being splined transversely to said work-supporting spindle, the adjacent ends of said two parallel shafts being connected by 35 change-gears providing two pairs of tooth contacts, the third shaft of said transmission being splined and arranged transversely to the other spindle and being connected by two pairs of gears to said other spindle and, 40 at its other end, being connected by a pair of gears directly to the splined one of said two parallel shafts, the other of said parallel shafts being connected to the work-spindle by a pair of gears; a prime-mover 45 geared directly to the intermediate splined shaft whereby power will be derived from its respective ends for driving said spindle-propeller shafts; and means for effecting a progressive feed of said head in a direction 50 parallel with the work-supporting spindle.

5. A hobbing-machine comprising a bed; a work-supporting spindle non-shiftably journaled in said bed near one end thereof; a relatively heavy stanchion shiftably supported thereon; a head slideable on said stanchion; a mounting swivelly affixed to said slideable head; a hob-supporting spindle journaled in said mounting to swivel therewith; a worm-wheel on the hob-supporting 55 spindle; a worm-wheel affixed to the work-supporting spindle; a transmission for driving said spindles and terminating at its ends in worms meshing respectively with said worm-wheels; and means for imparting 60 motion to said transmission.

6. A balanced-drive hobbing-machine comprising a bed; a relatively heavy stanchion mounted thereon; a work-supporting spindle supported by said bed; a splined transmission shaft journaled on said stanchion 70 parallel with said work-supporting spindle; an intermediate shaft and a parallel transmission shaft, each journaled on said bed transversely to said work-supporting spindle; change gears providing two pairs of 75 tooth contacts connecting said two parallel shafts; a head slideable on said stanchion; a hob-supporting spindle mounted on said head; a first worm and worm-wheel, the worm-wheel being affixed to said hob spindle; a pair of gears connecting said shaft with said worm; a pair of gears connecting said splined shaft to said intermediate shaft; and a second worm and worm-wheel connecting said parallel transmission shaft with 80 said work-spindle, the worm being mounted directly on said shaft and the worm-wheel being on said work-spindle.

7. A balanced-drive hobbing-machine comprising a bed; a relatively heavy stanchion shiftably supporting thereon; a work-supporting spindle non-shiftably journaled in said bed near one end thereof; a worm-wheel on said spindle; a splined transmission shaft journaled on said stanchion parallel 90 with said work-supporting spindle; an intermediate splined shaft and a parallel transmission shaft, each journaled on said bed transversely to said work-supporting spindle; change gears providing two pairs of 95 tooth contacts connecting said two shafts; a head slideable on said stanchion; a hob-supporting spindle mounted on said head; a worm-wheel on said spindle; a worm and a pair of gears connecting said hob-spindle 100 with said first-mentioned splined transmission shaft, one of said gears being splined to said shaft; a pair of gears connecting said first-mentioned splined shaft to said intermediate splined shaft, one of said gears being splined to said intermediate shaft; and a worm and worm-wheel connecting said 105 parallel transmission shaft with said non-shiftable work spindle.

8. A balanced drive hobbing-machine 115 combining a bed having a slideable stanchion; a head slideable thereon; a hob supporting spindle swivelly mounted on said head; a carriage fixed on said bed; a work-supporting spindle on said carriage; a 120 three-shaft transmission connecting said spindles, two of said shafts being journaled in parallelism on said bed and one of said parallel shafts being splined, the adjacent ends of said two parallel shafts being connected by change-gears providing two pairs of tooth contacts, the third shaft of said transmission being splined and arranged transversely to and connected with the splined one of said two parallel shafts by a 125 130

pair of gears; a prime-mover geared directly to the intermediate splined shaft whereby power will be derived from its respective ends for driving said spindle-
5 propelling shafts; a worm and worm-wheel directly connecting the work-spindle with the non-splined one of said parallel shafts; a pair of gears driven by the third splined transmission shaft; and a worm and worm-wheel for driving said hob-spindle by 10 motion derived from said pair of gears.

In witness whereof, I have hereunto subscribed my name.

WILLIAM F. ZIMMERMANN.
